[57] CLAIM

The ornamental design for a fluid delivery apparatus, as shown and described.

DESCRIPTION

FIG. 1 is a perspective view of a fluid delivery apparatus embodying our new design, showing a syringe installed;

FIG. 2 is a top plan view thereof, with the syringe removed;

FIG. 3 is a front elevational view of the apparatus shown in FIG. 2;

FIG. 4 is a left side elevational view of the apparatus shown in FIG. 2;

FIG. 5 is a right side elevational view of the apparatus shown in FIG. 2;

FIG. 6 is a rear elevational view of the apparatus shown in FIG. 2; and

FIG. 7 is a bottom plan view of the apparatus shown in FIG. 2.

The broken lines in FIG. 1, representing the syringe, are shown for illustrative purposes only.
